UNITED STATES PATENT OFFICE.

ISHMAEL G. CUTRIGHT AND JOHN A. SHARPS, OF BUCKHANNON, WEST VIRGINIA.
ASSIGNORS TO THE CUTRIGHT SHARPS COMPANY, INC., OF BUCKHANNON, WEST VIRGINIA.

SHADE-ROLLER.

1,389,579.

Specification of Letters Patent. Patented Sept. 6, 1921.

Application filed September 22, 1919. Serial No. 325,397.

To all whom it may concern:

Be it known that we, ISHMAEL G. CUTRIGHT and JOHN A. SHARPS, citizens of the United States, residing at Buckhannon, in the county of Upshur and State of West Virginia, have invented certain new and useful Improvements in Shade-Rollers, of which the following is a specification.

The invention relates to a roller, designed to receive an awning, shade, curtain, or the like which is adapted to be wound thereon, the invention being designed to provide a metal roller of unique construction which is internally braced, adapted to be lengthened or shortened and designed to be partly twisted so as to aline the awning, shade or the like attached thereto, whereby to cause the awning, shade, or the like to roll evenly when wound upon the roller.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

A preferred embodiment of the invention is illustrated in the accompanying drawing and on reference thereto;

Figure 1 is a side view of a roller constructed in accordance with the present invention and having an intermediate portion broken away.

Fig. 2 is a central longitudinal section looking toward the side of the roller provided with the curtain receiving slot.

Figs. 3 and 4 are opposite end views of the roller.

Fig. 5 is a cross section on the line 5—5 of Fig. 2.

Fig. 6 is a transverse section on the line 6—6 of Fig. 2.

Fig. 7 is a cross section on the line 7—7 of Fig. 2.

Corresponding and like parts are referred to in the following description and indicated in the several views of the drawing by like reference characters.

The roller 1 may be of any length and

diameter depending upon its particular adaptation. The roller is formed from a strip or ribbon of sheet metal of suitable gage, which is bent between its longitudinal edges into cylindrical form. The edge portions of the strip or ribbon are spaced apart to form a longitudinal slot 2 which is adapted to receive the end of the curtain, or like part to be attached to the roller. The edge portions of the strip, bordering upon the slot 2 are recurved, as indicated at 3, to stiffen and reinforce the roller and to obviate the formation of sharp edges which would tend to cut or otherwise injure the awning, shade, or curtain. Moreover, the recurved edge portions 3 engage the horns or ends of crescent shaped braces 4 and retain them in proper position, said braces in turn preventing the spread or enlargement of the roller. Each of the braces 4 is provided with laterally extending ears 5 at its outer edge and these ears project in opposite directions and engage the inner wall of the roller and hold the brace perpendicular thereto. The ears 5 form an integral part of the braces and engage the inner wall of the roller with sufficient friction to hold the brace in the adjusted position. As indicated in Fig. 2 the roller is provided in its length with a plurality of braces which may be spaced apart any desired distance, according to the desired resistance to be offered by the roller against external pressure.

The roller is closed at its ends in any desired way. A cap 8 is fitted to one end of the roller and is formed with a central opening 9 to receive a pintle. The cap 8 has a rim or flange 10 which slips into the roller. The rim 10 has a portion cut therefrom, as indicated at 11, to receive the recurved edges 3 of the roller. The end portions of the rim or flange 10 bordering upon the cut-out notch 11 engage the spaces formed by the recurved edge portion 3, thereby preventing the spread of the roller and insuring the end piece or cap 8 being retained in place. Ordinarily, the friction between the parts in contact is sufficient to retain the cap 8 in proper place.

The opposite end of the roller is provided

with an adjustable section 12, which telescopes therewith, thereby enabling the length of the roller to be varied within certain limits. It is to be understood that sections 12 of various lengths will be provided, so that a section of desired length may be selected for use with the roller. Each section 12 comprises a tubular portion and a cap or end piece 13. This cap or end piece 10 is similar in construction to the cap or end piece 8 and the rim or flange is soldered to the outer end of the section 12 of which it forms a part. The section 12 is formed with a longitudinal slot to receive the recurved edge portions 3 of the roller 1, as indicated most clearly in Fig. 7. The outer end of the slot formed in the side of the section 12 is flared, as indicated most clearly in Fig. 2 to facilitate the entrance of the section 15 when placing the same in the roller 1. The cap or end piece 13 is provided with a centrally disposed pintle 14 to coöperate with a suitable fixture when the roller is mounted.

A tubular stay 15 is secured within the 20 end of the roller adapted to receive the adjustable section 12. The stay 15 is of tubular form and is provided in one side with a slot to receive the recurved edge portions 3 of the roller. The ends of the stay bordering upon the slot are soldered or otherwise 25 fixedly secured to the recurved edge portions 3 of the roller 1. The stay 15 is relatively short, being approximately about three inches in a roller of approximately 30 four feet in length. Obviously the stay 15 may be of any length. The stay 15 is constructed of annealed or relatively pliable sheet material, so that it may be bent and retain the shape imparted thereto. One 35 advantage of the stay 15 is to preserve the adjusted shape of the roller 1. Under ordinary conditions the slot 2 in the side of the roller 1 is parallel with the axis of the roller. However, should it be required to 40 relatively incline the slot 2 in order to cause the curtain or like to wind evenly on the roller, said slot may be adjusted by gripping opposite ends of the roller and imparting a twist thereto. The twist thus given 45 to the roller will adjust the slot 2 so as to cause the curtain, or like part to roll evenly when wound upon or unwound from the roller. The partial twist given to the roller 50 1, is maintained by the stay 15, which as stated, is formed of annealed or relatively pliable sheet metal, so that it will retain the adjusted position imparted thereto. As before stated, the slot 2 receives the end of the material constituting, shade, awning, curtain, or like part to be wound upon the roller, said end being retained within the roller in any desired way. The crescent form of the 55 braces 4 and the tubular form of the stay 15 provide for receiving the end of the curtain and its fastening means.

Having thus fully described our invention, what we claim as new and desire to secure by Letters Patent is:—

1. A metal roller having a longitudinal slot and braces positioned in the roller so as to lie in planes transverse to the axis of the roller, said braces having an approximately crescent shape and disposed with their horns upon opposite sides of the slot. 70
2. A metal roller having a longitudinal slot, and braces positioned in the roller so as to lie in planes transverse to the axis of the roller, said braces having an approximately crescent shape and disposed with their horns upon opposite sides of the slot, 80 and laterally extending ears provided on the outer edges of said braces so as to engage the inner wall of the roller. 85
3. A metal roller having a longitudinal slot in a side thereof and having the portions defining the walls of the slot recurved and crescent shaped braces positioned in the length of the roller so as to lie in planes transverse to the axis of the roller and having their horns engaging the recurved edge 90 portions of the roller. 95
4. A metal roller having a longitudinal slot in a side thereof and having the portions defining the walls of the slot recurved and crescent shaped braces positioned in the length of the roller so as to lie in planes transverse to the axis of the roller and having their horns engaging the recurved edge 100 portions of the roller and provided at their outer edges with oppositely extending ears to engage the inner wall of the roller. 105
5. A metal roller having a longitudinal slot in a side thereof and a tubular stay within the roller and having a longitudinal slot in a side thereof to register with the slot of the roller, said stay having the edge portions defining the walls of the slot secured to the edge portions of the roller adjacent the slot, said stay being of pliable metal to yield and hold the roller in the required adjusted position when partly twisted to cause the curtain, or like part to roll evenly thereon. 110
6. A metal roller having a longitudinal slot in a side thereof and having edge portions defining the walls of the slot recurved and a tubular stay of less diameter than the roller and disposed therein and formed in a side with a slot and having the edge portions adjacent the slot secured to the recurved edge portions of the roller. 115
7. A metal roller having a slot in a side thereof and having the edge portions defining the walls of the slot recurved and an end piece provided with an extension to enter the roller and cutaway to clear the recurved edge portions of the roller and engage therewith. 125
8. A metal roller having a longitudinal slot in a side thereof, with the edge por- 130

tions defining the walls of the slot recurved and a section telescoping with the roller and comprising a tubular portion having a slot in a side thereof and provided at its outer end with a cap, the edge portions of the tubular part bordering upon the slot engaging the recurved edge portions of the roller.

In testimony whereof we affix our signatures in presence of two witnesses.
